J. A. EARLEY.
ATTACHMENT FOR POWDER MACHINES.
APPLICATION FILED SEPT. 21, 1915.

1,192,769.

Patented July 25, 1916.

UNITED STATES PATENT OFFICE.

JAMES A. EARLEY, OF WILMINGTON, DELAWARE.

ATTACHMENT FOR POWDER-MACHINES.

1,192,769.

Specification of Letters Patent. Patented July 25, 1916.

Application filed September 21, 1915. Serial No. 51,853.

To all whom it may concern:

Be it known that I, JAMES A. EARLEY, a citizen of the United States, residing at Wilmington, in the county of New Castle, 5 State of Delaware, have invented certain new and useful Improvements in Attachments for Powder-Machines; and I do hereby declare the following to be a full, clear, and exact description of the invention, 10 such as will enable others skilled in the art to which it appertains to make and use the same.

This invention relates to improvements in attachments for powder machines.

15 One object of the invention is to provide a novel distributor for the streams of the plastic mass which is forced from the dies.

Another object is to provide a device for attachment to a powder molding machine 20 which will effectively distribute the streams of powder into various receptacles disposed to receive the material.

A further object is to provide means for preserving the even temperature of the distributor so that the streams of powder will 25 not adhere to the discharge spouts and tubes.

Other objects and advantages will be apparent from the following description when taken in connection with the accompanying 30 drawing.

In the drawing: Figure 1 is an elevation of my distributor; Fig. 2 is a top plan view; Fig. 3 is a vertical section on the line 3—3 of Fig. 1; Fig. 4 is a horizontal section on the line 4—4 of Fig. 1; Fig. 5 is a horizontal section on the line 5—5 of Fig. 1; and Fig. 6 is a perspective view of one of the lower tubes.

Referring particularly to the accompanying drawing, 10 represents the die portion of a powder molding machine. Disposed below this die member is a truncated cone-shaped member which includes a top plate 11 formed with a plurality of openings 12, 15 a bottom plate 13 being also formed with a plurality of openings 14, and the surrounding or inclosing wall 10'. Connected to the top and bottom plates and extending down-

wardly and outwardly between the openings of the top and bottom plates are a plurality 50 of downwardly flaring tubes 15. Secured to the lower face of the plate 13 is the perforated top plate 16' of a casing 16, the upper plate of said casing being circular while the lower plate is rectangular, said upper 55 and lower plates being connected by the inclined wall 17.

In the bottom plate 18 of the casing 16 are a plurality of openings 19, and connecting these openings with the openings 14 of 60 the plate 13 are a plurality of downwardly and outwardly extending pipes 20. Depending from the lower ends of these pipes 20 are a plurality of discharge spouts 21 from which the powder issues in streams 65 and is collected in receptacles disposed therebeneath. It will be understood that when one receptacle is filled the stream of powder can be cut off with a suitable instrument, the receptacle removed and an empty receptacle 70 put in its place. Extending into the distributor, and among the pipes 20 is a steam pipe 22 which keeps the distributor at an even temperature so that the streams of powder passing through the pipes will not 75 stick to the sides of the pipes.

What is claimed is:

An attachment for a powder machine comprising a truncated cone-shaped casing detachably secured to the discharge portion 80 of the machine, a second casing secured below the bottom of the first casing, the top of the second casing being circular in plan while the bottom is rectangular in plan, a plurality of powder passage pipes extending 85 through both of the said casings in downwardly and outwardly inclined directions, nozzles carried by the lower ends of the pipes, and a heat conductor extending through the casings. 90

In testimony whereof, I affix my signature, in the presence of two witnesses.

JAMES A. EARLEY.

Witnesses:

DANIEL E. KELLY,
JAMES F. EARLEY.
